UNITED STATES PATENT OFFICE

134,412

DESIGN FOR AN APPLIQUE EMBLEM

Nathan Milgram, John C. Johnsen, Ford Smith, and Benjamin Sosland, Kansas City, Mo., assignors to The American War Dads, Kansas
City, Mo., a corporation of Missouri

Application September 2, 1942, Serial No. 108,111

Term of patent 14 years

To all whom it may concern:

Be it known that we, Nathan Milgram, John C. Johnsen, Ford Smith, and Benjamin Sosland, citizens of the United States, residing at Kansas City, in the county of Jackson and State of Missouri, have invented a new, original, and ornamental Design for Applique Emblem, of which the following is a specification, reference being had to the accompanying drawing, forming part thereof.

Fig. 1 is an elevational view of an applique emblem showing our new design.

Fig. 2 is an edge view thereof.

We claim:

The ornamental design for an applique emblem, substantially as shown.

NATHAN MILGRAM.
BENJAMIN SOSLAND.
JOHN C. JOHNSEN.
FORD SMITH.
